UNITED STATES PATENT OFFICE.

GEORGE W. WACKER, OF RUTHERFORD, NEW JERSEY, ASSIGNOR TO NATIONAL CARBON COMPANY, INC., OF NEW YORK, N. Y., A CORPORATION OF NEW YORK.

ELECTRIC ENGINE-STARTER.

1,330,101.

Specification of Letters Patent. Patented Feb. 10, 1920.

Application filed December 14, 1917. Serial No. 207,098.

To all whom it may concern:

Be it known that I, GEORGE W. WACKER, a citizen of the United States, residing at Rutherford, county of Bergen, State of New Jersey, have invented a certain new and useful Improvement in Electric Engine-Starters, of which the following is a specification, reference being had therein to the accompanying drawings, forming part thereof.

10 My invention relates to electric engine-starting apparatus of that type in which a dynamo electric machine is arranged to be connected to the engine shaft for effecting an engine-cranking operation through a set 15 of speed reducing gearing and an automatically acting one-way or unidirectional clutch, and in which when the engine starts and becomes self-actuating at an accelerated speed, this automatic clutch discontinues the 20 operation of the gearing and another automatically acting one-way or unidirectional clutch connects the engine shaft to the dynamo electric machine for operating the latter as a generator without the operation 25 of the gearing. An early example of this type of engine-starting apparatus is disclosed in the patent to Clyde J. Coleman, No. 745,157 of November 24, 1903, for means for operating motor vehicles; and a later and 30 highly developed example of this type of engine-starting apparatus is disclosed in the patent of Henry Gibson O'Neill, No. 1,315,790, dated September 9, 1919, for electrical engine-starting apparatus, for which 35 the application was filed September 21st, 1915. My present invention is an improvement upon or further development of the electrical engine-starting apparatus disclosed in the above noted patent of Henry Gibson 40 O'Neill.

It is commonly recognized in the art that some provision must be made to prevent the starting apparatus from being damaged or broken by reason of the reverse operation of 45 the engine, or as it is commonly called, "back firing." Heretofore in some cases as a measure of protection, a back fire clutch has been interposed in the connections between the starting apparatus and the engine, but in 50 view of the fact that such engine connections are subjected to a heavy torque, particularly in the engine-starting operation, it is necessary that a back fire clutch in this location must be very large and strong in order to 55 withstand the excessive strain and even then

has been found liable to get out of working condition, and also in such cases this back fire clutch has to be provided as a separate piece of mechanism, thereby adding considerably to the expense of manufacture. In 60 other cases heretofore, safety has been sought in the provision of some means for compelling the spark advancing and retarding device of the engine to be moved to the retarded spark position before the engine-starting 65 apparatus could be operated to crank the engine, and the above noted patent of Henry Gibson O'Neill discloses means for automatically retarding the spark subsequent to the operation of the engine-starting apparatus, the object in all such cases being to 70 prevent a reverse operation or back fire of the engine. However, it has been found in practice that in some cases the adjustment of the spark advancing and retarding device of 75 the engine is not such as to effect a fully retarded spark condition when it is supposed to do so and thus the partly advanced spark will sometimes cause a back fire in the engine. Also it has been found that in some 80 cases a driver or chauffeur will disregard the automatic safety means provided for retarding the spark and will purposely advance the spark so as to make the starting operation easier by reason of the fact that 85 with an advanced spark the charge will be under greater compression when the ignition spark is produced. My invention permits other safety means to be dispensed with, or it may be employed in conjunction there 90 with, as desired.

In an electrical engine-starting apparatus of the type above noted employing gearing and two automatically acting one-way clutches, when the engine back fires or reverses its operation both of these clutches will become locked, thereby throwing a very excessive strain upon the engine-cranking mechanism, and it has been found in practice that damage and breakage commonly 100 result, and in the engine-starting apparatus disclosed in the above noted patent of Henry Gibson O'Neill it has been found that such damage or breakage usually takes place in the one-way clutch through which the 105 dynamo electric machine is driven by the engine as a generator.

An object of my invention is to provide a simple, compact and inexpensive back fire clutch built into and combined with the 110

mechanism of the engine-starting apparatus, and particularly in the engine-starting apparatus substantially as disclosed in the above noted patent of Henry Gibson 5 O'Neill. Other objects and advantages of my invention will hereinafter appear.

In accordance with my present invention a back fire clutch is incorporated into and forms a part of the engine-starting apparatus, and is so arranged that the only strain or torque to which it is subjected is that of driving the dynamo electric machine as a generator, not being in use at all in the engine-starting operation, thereby permitting 15 of a small, compact and inexpensive construction of this part of the apparatus. In carrying out my invention a back fire clutch such as a friction clutch is combined with one of the automatically acting unidirectional clutches in an electric engine-starting apparatus of the type above noted, and more particularly with the automatic one-way clutch through which the dynamo electric machine is driven as a generator from 20 the engine. My invention includes in this connection various features of construction and combinations of parts, as will appear from the following description.

I shall now describe the electric engine-starter embodying my invention illustrated in the accompanying drawings and shall thereafter point out my invention in claims.

Figure 1 is a vertical longitudinal section of the electric engine-starter shown in attached position on a motor vehicle as viewed from the right side thereof.

Fig. 2 is a slightly reduced partial transverse section on planes indicated by the offset line 2—2 of Fig. 1 as viewed from the 40 right.

Fig. 3 is a side elevation as viewed from the left in Fig. 2 with parts omitted.

Fig. 4 is a slightly reduced transverse section on a plane indicated by the line 4—4 45 of Fig. 1 as viewed from the left.

Fig. 5 is a similar section indicated by the line 5—5.

Fig. 6 is a greatly enlarged perspective view of a clutch member hereinafter described.

Fig. 7 is a similar view of another clutch member which is coöperative with that appearing in Fig. 6.

Fig. 8 is an elevation of these coöperative clutch members in coöperative relation in the position in which they appear as viewed in Fig. 5.

Fig. 9 is a diagrammatic representation of the electric circuits and engine-starting 60 apparatus.

In the electric engine-starter illustrated in the accompanying drawings, the back fire clutch as a feature of my invention is incorporated in and combined with the mechanism of the engine-starting apparatus, and

is shown as combined with an automatically acting one-way or unidirectional clutch through which driving power is transmitted from an engine connected member to the armature of a dynamo electric machine for 70 operating such machine as a generator. An expanding split friction ring 1 of suitable resilient material such as steel, and having separated or spaced ends as shown in the drawings, is adapted to expand within and 75 frictionally engage the smooth inner annular surface or cylindrical bore of an intermediate clutch member or cam ring 2 within which the expanding resilient split ring 1 forms an inner clutch member, the frictional engagement between the inner and intermediate clutch members 1 and 2 being sufficient for the normal operation of driving the dynamo electric machine as a generator, as will presently appear, but these 80 frictionally engaged clutch members 1 and 2 are adapted to yield rotatively and slip relatively to each other under an excessive strain or torque which might endanger any part of the apparatus.

A flanged outer clutch member or clutch ring 3 surrounds the intermediate clutch member or cam ring 2 and forms therewith an automatically acting unidirectional or one-way clutch, a gripping roller or clutch roller 4 being interposed between the intermediate and the outer clutch members 2 and 3, and being shown as resiliently pressed toward the engaging position by a small compression spring 5. An operating stud 6 is located between the spaced or separated ends of the expanding spring friction ring 1 and projects from and is shown as a lug formed integral with the forward part of a two-part gearing carrier 7, the two parts 105 of which are firmly secured together by means of four rivets 8 and two dowel pins 9 appearing in Fig. 4. The rear part of the gearing carrier 7 has a rearwardly projecting boss or hub which, as appears in 110 Fig. 1, is fixed upon the rear end of an engine connected starter shaft 10. The outer clutch member or clutch ring 3 at its forward side is provided with a hub which is fixed upon a tubular armature shaft 11 115 which is loosely journaled upon the starter shaft 10, as appears in Fig. 1. The split clutch ring 1 which frictionally engages within the cylindrical bore of the clutch cam 2 fits loosely around the tubular armature 120 shaft 11, for free relative rotation of the armature shaft 11 in the split clutch ring 1.

The tubular armature shaft 11 has gear teeth thereon at its rear end forming a pinion which engages with a pair of planetary spur pinions 12 journaled by means of bushings, as shown in the drawings, on bearing pins 13 in the gearing carrier 7. The gearing carrier 7 peripherally supports and is rotative relatively to a combined 130

gear ring and ratchet ring 14 having internal gear teeth engaged by the planetary pinions 12, and this gear ring 14 is provided with peripheral ratchet teeth adapted to be engaged by a pivoted clutch pawl 15 forming therewith an automatically acting unidirectional or one-way clutch for holding the gear-ring 14 stationary during an engine-starting or engine-cranking operation. The clutch pawl 15 is pivoted on a bearing pin 16 which is supported by a flanged stationary frame 17, and this clutch pawl 15 is electrically controlled, as will hereinafter appear, so that during the operation of the dynamo electric machine as a generator it will not rattle or knock against the ratchet teeth of the gear ring 14.

The starter shaft 10 is journaled at its front end in bearings in a front yoke or frame 18, and at its rear end is similarly journaled in bearings in a rear casing part or housing 19. A cylindrical shell forming a magnetizable magnet frame 20 is interposed between the front yoke 18 and the rear housing 19, and the front yoke 18 and magnet frame 20 are shown as supported upon the housing 19 by means of two upper longer bolts 21 and two lower shorter bolts 22, as appears in the drawings. The magnet frame 20 carries inwardly projecting usual pole pieces 23 upon which are the field coils, shown as a series winding 24 and a shunt winding 25, as appears in Fig. 9 more particularly. The tubular armature shaft 11 has fixed thereon a rotative armature 26. The starter shaft 10 at its rear end is rotatively coupled to the engine shaft 27 by means of a short intermediate coupling shaft 28 and a spring-pressed coupling sleeve 29, the spring 30 for which surrounds the coupling shaft 28, as appears in Fig. 1.

The clutch pawl 15 which co-operates with the ratchet teeth of the gear ring 7 is electrically controlled by means of a solenoid having a coil 31 and a magnetic field frame or yoke 32 shown as formed in one piece with the flanged supporting frame 17 which is attached to and supported by the housing 19. The solenoid is shown as arranged diagonally or at an angle in the lower part of the housing 19 at the right side thereof as viewed from the rear, as appears in Fig. 4. A movable solenoid core or plunger 33 is adapted to be magnetically drawn upward into the coil 31, and is retracted by means of a coiled thrust spring 34. At its upper end the magnetic core or solenoid plunger 33 is provided with a rigidly projecting non-magnetic extension or connecting rod 35 for operating the clutch pawl 15. When the solenoid coil 31 is energized the clutch pawl 15 is moved to the engaging position by the operating rod 35 through the intermediary of a sheet metal clip or yoke 36 and an interposed coiled spring 37 which forms a re-

silient yielding connection, and the pivoted pawl 15 is moved to the free or disengaged position directly by the clip or yoke 36, which is pivoted on the bearing pin 16 of the clutch pawl 15 and has a free projecting end which enters a hole or opening in one side of the connecting rod or operating rod 35, as appears in Fig. 4 of the drawings, this disengaging movement of the clutch pawl 15 being imparted by the plunger-retracting spring 34 when the solenoid coil 31 is de-energized, as will be readily understood. The solenoid coil 31 is in an energized condition during an engine-cranking operation, the dynamo electric machine being then operated as a motor, and is in a de-energized condition during the time that the dynamo electric machine is operated as a generator, as will presently appear.

In the particular construction of electric engine-starter illustrated in the drawings the solenoid having the coil 31 also acts as a relay for controlling the electric circuits of the dynamo electric machine in its operation as a motor for cranking the engine or as a generator. At its outer or projecting lower end beyond the thrust spring 34 the solenoid plunger 33 carries a switch blade 38 shown as made up of several leaves or parts and which, as indicated in the drawings, is insulated from the solenoid plunger 33. In the retracted position of the solenoid plunger 33, as appears in Figs. 4 and 9 of the drawings, the switch blade 38 will form an electrical connection between a pair of contact plates 39 mounted upon and insulated from a support or base 40 which is secured to the magnet frame 32, these contact plates 39 forming part of the generating circuit of the dynamo electric machine as will presently appear. When the solenoid coil 31 is energized the switch blade 38 will move away from the contact plates 39, thereby breaking the generating circuit, and will make electrical connection between a pair of contact blocks 41 insulated from the contact plates 39 and also insulated from the supporting plate 40 upon which they are mounted, these contact blocks 41 forming a part of the engine-cranking circuit of the dynamo electric machine operated as a motor as will presently appear.

Reference will now be had to Fig. 9 illustrating the electric circuits, which are shown as of the single wire or grounded type. When the dynamo electric machine is operated as a generator, there is a circuit which includes a grounded connection or conductor 42, the armature 26, the series field winding 24, a conductor 43, the upper or left contact block 41, a conductor 44, a current regulating device 45, which may be of any suitable construction, as is well understood in the art, a conductor 46, the lower or right contact block 41, and a line conductor or main con-

ductor 47 to a storage battery 48 having a ground connection 49, this being the armature and series field circuit of the dynamo electric machine operated as a generator.

- 5 The shunt circuit includes a conductor 50 connected to the ground lead 42, the shunt winding 25, a conductor 51, the upper or left contact plate 39, the switch blade 38, the lower or right contact plate 39, a conductor 52, the current regulator 45, and the conductor 46 and other above described connections to the battery 48. A lighting circuit 53 is shown as connected to the main conductor 47 and has therein a usual 15 switch 54.

For operating the dynamo electric machine as a motor to effect an engine-cranking operation, the solenoid coil 31 is energized and operates to move the pivoted pawl 15 into engagement with the peripheral ratchet teeth of the gear ring 14, and also operates to move the switch blade 38 out of contact with the contact plates 39 and into contact with the contact blocks 41. The energizing 25 circuit of the solenoid coil 31 includes a conductor 55 connected to the main conductor 47, and a conductor 56 adapted to be connected to a ground lead 57 by means of a starting switch 58.

- 30 The operation of the electric engine-starter of my invention will now be more particularly noted and described. When the dynamo electric machine is operated as a motor to crank the engine, the pawl 15 is in 35 engagement with the peripheral ratchet teeth of the gear ring 14, forming therewith an automatically acting one-way or unidirectional clutch, and as the armature 26 and its tubular shaft 11 rotate in a counter-clockwise direction as viewed from the left in Fig. 1, and as seen in Figs. 4 and 5, it will be evident that a clockwise torque impulse will be imparted to the gear ring 14, but this gear ring will be held against rotation 40 by the engaged clutch pawl 15, so that the counter-clockwise rotation of the armature shaft 11 through the pinions 12 will impart rotation in the same or counter-clockwise direction to the gearing carrier 7 at a reduced 45 rate, which will be transmitted through the starter shaft 10, coupling shaft 28, and coupling 29 to the engine shaft 27 for rotating the latter to start the engine.

It is now to be noted that in the engine-cranking operation the armature 26 and the engine connected gearing carrier 7 are both rotating in the same direction, but that the armature 26 together with its shaft 11 and the outer clutch member 3 rotates at a much 55 higher rate of speed than does the gearing carrier 7, which through its projecting lug 6 and the split friction ring 1 carries the intermediate clutch member or clutch cam 2. In view of this more rapid rotation of the 60 outer clutch member 3 in relation to the in-

termediate cam ring 2, the interposed gripping roller 4 will be in a disengaged condition, and the outer clutch member or clutch ring 3 will rotate freely upon and relatively to the more slowly moving intermediate 70 clutch member or clutch cam 2 which will rotate at the same rate as the gearing carrier 7 without any slipping taking place between the split friction ring 1 and the clutch cam 2 which it frictionally engages, 75 as hereinbefore described.

It will now be clear that in the engine-cranking operation the engine shaft 27 will be rotated at a reduced rate from the armature shaft 11 through the planetary gearing, the automatically acting one-way clutch provided by the ratchet teeth on the gear ring 14 and the automatically controlled clutch pawl 15, and that all parts of the other automatically acting unidirectional clutch comprising the outer clutch member 3 and intermediate clutch member or clutch cam 2 will be idle, as also will be the frictional back fire clutch comprising the intermediate clutch member or clutch 80 cam 2, the split friction ring 1 and its operating stud or lug 6 on the gearing carrier 7.

As soon as the engine starts and thereby through its own power become self-actuating, the rotative speed of the engine shaft 95 27 and connected parts including the gearing carrier 7 will be accelerated and a reversal of torque impulse on the gear ring 14 will take place with the result that the gear ring 14 will partake of the rotation of 100 the gearing carrier 7 and the ratchet teeth of the gear ring 14 will disengage from the pawl 15 automatically. Also the accelerated speed of rotation of the gearing carrier 7 will be imparted to the intermediate clutch 105 member or clutch cam 2 through the intermediary of the operating stud 6 and friction ring 1, thereby causing the gripping roller 4 to engage with the outer clutch member or clutch ring 3 which, as hereinbefore noted, is fixed on the armature shaft 11, so that now after the engine has started the armature 26 will be driven from the engine shaft 27 through the automatically acting one-way clutch comprising the outer 110 clutch ring 3 and the clutch cam 2, and also through the back fire friction clutch comprising the friction ring 1 and the intermediate clutch member 2, it being noted that the back fire clutch is combined with 115 this armature-driving unidirectional clutch.

The engine-starting switch 58 may now be opened to deenergize the solenoid coil 31 whereby the spring 34 will retract the solenoid plunger 33, thereby moving the free 120 end of the pivoted clutch pawl 15 out of the path of the peripheral ratchet teeth of the rotating gear ring 14, and also concurrently opening the engine-starting motor circuit and closing the generating circuit 125 130

as hereinbefore described. With the opening of the engine-starting switch 6, the dynamo electric machine will be operated as a generator, and in this energy generating 5 operation the armature 26 will be driven from the gearing carrier 7 through the projecting lug 6, split friction ring 1, intermediate clutch member 2, gripping roller 4 and outer clutch member 3, and in this 10 connection it is to be noted that the expanding split friction ring 1 has a frictional engagement with the intermediate clutch member 2 sufficient for thus operating the dynamo electric machine as a generator 15 without slippage. When the split friction ring 1 is operated as above described to drive the armature 26 in the operation of the dynamo electric machine as a generator, it is to be noted that the push or thrust of the 20 operating stud 6 upon one of the ends of this split ring 1 will have a tendency to further expand the ring 1 and thereby to increase the driving friction of this ring 1 upon the cylindrical surface within the 25 intermediate clutch member 2.

However, we will now suppose, as occasionally happens, that instead of the engine starting in the normal or forward direction of rotation that it back fires or starts in 30 the reverse direction of rotation. The engine is so powerful that the engine-starting torque of the armature 26, even with the leverage obtained through the speed reducing gearing, will be insufficient to resist 35 the enormous torque of the engine, and in view of the fact that the clutch pawl 15 is in engagement with the peripheral ratchet teeth of the gear ring 14, and that in this reversed operation of the engine the torque 40 upon the gearing carrier 7 will be in a clockwise direction, as viewed from the left in Fig. 1 and as appears in Figs. 4 and 5, the clutch pawl 15 will hold the gear ring 14 in a locked condition against such rotation, 45 and the result will be that reversed rotation will be imparted to the armature 26 through the planetary pinions 12 and the gear teeth which form the pinion upon the inner end of 50 the armature shaft 11. The stationarily locked gear ring 14, the planetary pinions 12 and the pinion formed on the armature shaft 11 constitute multiplying gearing, through which the armature shaft 11 will be rotated in a reverse direction at a higher 55 rate of speed than the gearing carrier 7 is rotated in the same direction. The outer clutch member or clutch ring 3 which is fixed upon the armature shaft 11 will now rotate in this reverse direction at a more 60 rapid rate than the clutch cam or intermediate clutch member 2 which is carried by the gearing carrier 7, and by reason of this differential or relative rotation the gripping roller 4 will be engaged and will lock 65 the outer clutch member or clutch ring 3 to

the intermediate clutch member or clutch cam 2.

If the intermediate clutch member or clutch cam 2 were fixed upon or rigidly carried by the gearing carrier 7 as has been the 70 case heretofore in similar constructions, no relative rotation could then take place between the armature shaft 11 and the gearing carrier 7, this being by reason of the outer clutch member 3 being locked to the 75 clutch cam 2; and in view of the fact, as above noted, that the gear ring 14 is locked in a stationary condition by the clutch pawl 15, the engine shaft 27 and all of the engine connected parts including the gearing 80 carrier 7 would be in a locked condition. Under such circumstances the engine-starting mechanism has proved unequal to the enormous strain developed by such a reverse operation of the engine, with the 85 result that breakage has taken place, and commonly heretofore the undirectional clutch corresponding to the outer clutch ring 3 and clutch cam 2, has been broken. However, in the operation of my invention, 90 when the intermediate clutch member or clutch cam 1 is locked to the outer clutch member 3 by the interposed gripping roller 4, as above described, the intermediate clutch member or clutch cam 2 will partake 95 of the reversed rotation of the outer clutch member 3 and will slip upon the split friction ring 1, which through its engagement with the lug 6 of the gearing carrier 7 is rotating in the same reverse direction but at 100 a lower rate of speed. The slippage of the clutch member 2 upon the friction ring 1 has been found effectually to guard against and prevent the breaking of any part of the 105 starter mechanism under such reverse operation or back firing of the engine.

It is obvious that various modifications may be made in the construction shown in the drawings and above particularly described within the principle and scope of my 110 invention.

I claim:

1. In electric engine-starting apparatus in which a dynamo electric machine is operated as a motor for effecting an engine-starting 115 operation through a set of speed reducing gearing and an automatically acting one-way clutch and when the engine has started said clutch discontinues the operation of the gearing and the dynamo electric machine is 120 operated as a generator through another automatically acting one-way clutch, the combination with one of said clutches of a yieldable clutch including a resiliently acting split friction ring arranged so as to permit the engine-starting and energy generating operations but adapted to yield within a margin of safety so as to prevent breakage by reason of a back fire or reverse operation of the engine. 125

2. In an electric engine-starting apparatus comprising a dynamo electric machine having a rotative armature, a planetary gearing carrier rotative about the same axis as the armature, a planetary gear ring concentric with and relatively to which said gearing carrier and armature are rotative, an automatically acting driving clutch for connecting the gearing carrier to the armature for operating the dynamo electric machine as a generator without the operation of the planetary gearing, and an automatically acting engine-starting clutch for locking the planetary gear ring against rotation thereby to render the planetary gearing operative for starting the engine through the planetary gearing from the dynamo electric machine operating as a motor, characterized by said driving clutch including an outer member carried by said armature and an intermediate member coöperative with said outer member, and in combination with a yieldable clutch including an expanding split ring located within and frictionally engaging said intermediate clutch member and said split ring being connected to said gearing carrier.
3. The invention claimed in claim 2 in which said gearing carrier is connected to said split ring of the yieldable clutch by means of a stud or lug which projects from the gearing carrier between the spaced ends of said split ring.
4. An electric engine-starter having, in combination, a dynamo electric machine having a rotative armature and armature shaft, a unidirectional clutch having an outer member carried by said armature shaft and having an intermediate member coöperative with and located concentrically within said outer member, an expanding split friction ring frictionally fitting within said intermediate clutch member and forming therewith a yieldable friction clutch, and a rotative member having a driving lug extending between the spaced ends of the split ring of said friction clutch.

5. The invention claimed in claim 4 in which said rotative driving member forms part of a planetary gear set through which by means of a unidirectional starting clutch the armature shaft of the motor is adapted to effect an engine-starting operation.

6. Clutching means for electrical engine-starting apparatus, such clutching means comprising a one-way clutch including two members and yieldable clutching means combined with one of said members and including a resiliently acting split friction ring.

7. Clutching means for electric engine-starting apparatus comprising a unidirectional clutch having coöperative members one of which has therein a bore forming an annular friction surface, a yieldable clutch having an expanding split friction ring frictionally engaging within said bore, and operating means for said split ring including a stud projecting between its spaced ends.

8. Clutching means for electric engine-starting apparatus comprising a unidirectional clutch having coöperative members one of which has an annular friction surface, a yieldable clutch having a resiliently acting split friction ring frictionally engaging said annular friction surface, and operating means for said split ring.

9. An electric engine-starter having, in combination, a dynamo electric machine having a rotative armature and armature shaft, a unidirectional clutch having a clutch member carried by said armature shaft and having a second clutch member coöperative with said clutch member on the armature shaft, a resiliently acting split friction ring frictionally engaging with said second clutch member and forming therewith a yieldable friction clutch, and a rotative engine connected member connected to the split ring of said friction clutch.

In testimony whereof, I have affixed my signature to this specification.

GEORGE W. WACKER.
